Frank J. Kent

UNITED STATES PATENT OFFICE.

SIMON COOPER, OF BROOKLYN, NEW YORK.

ELECTRICAL SOSTENUTO PIANO.

Application filed December 3, 1918, Serial No. 265,083. Renewed November 19, 1925.

My present invention relates to what are known as electrical sostenuto pianos.

One of the principal objects of the invention is to synchronize the impulses of an actuating electromagnet with the natural vibrations of the sonorous body which it actuates, which latter, by way of illustration, may be a piano string.

Another object of the invention is to provide a simple and inexpensive arrangement of circuit controller for the electromagnet, capable of being readily adjusted to secure synchronization between the electrical impulses of the magnet with the vibrating movements of the string or other vibratory member.

I have accomplished the foregoing and other objects in my invention, by controlling the actuating electromagnet from circuit contacts under control of the string or other vibrated member and by relatively adjusting said contacts angularly one about the other to a point where the propelling impulses set up in the magnet are in time with the natural vibrations of the vibratory member.

Other features of the invention will appear as the specification proceeds, attention being now invited to the accompanying drawing forming a part hereof and wherein I have disclosed the invention embodied in a concrete practical form.

In this drawing, Figure 1 is a partly sectional and more or less diagrammatic view of a form of the invention as adapted to a sostenuto piano, Figure 2 is a sectional view taken on line 2-2 Figure 1, and Figure 3 is a modified form showing the parts in a slightly adjusted position.

In Figure 1 the vibratory member, which in this case is the piano string, is designated 5, the magnet for vibrating the string is designated 10, and the magnet-controlling piano key is indicated at 7. This key, when depressed, closes a switch 8, which completes an electric circuit through the electromagnet, said circuit including a battery or other source of current 9 and being under the control of a circuit controller which is controlled by the vibrating string.

This circuit controller is of novel construction, embodying an outstanding contact 18, carried by the string, having a down-turned angularly-directed end terminal portion 19, and a relatively stationary cooperating contact 16 having a terminal offset arm desig-

nated 16', said contact 16 being mounted on a support 20, which latter may simply be a part of the piano frame. The stationary arm 16' may have an angular sliding or sweeping engagement with the string-carried contact, as will be clear from Figure 2.

These contacts are relatively adjustable angularly, one about the other, for the purpose of varying the point of engagement between the two. Thus in Figure 2 the relatively stationary contact arm 16' is shown positioned to engage the vibratory contact at one side thereof, while in Figure 3 this contact is shown adjusted to a position approximately in front of the string. For the purpose of obtaining such adjustments one or both said contacts may be made adjustable, for instance by making them of bendable material. Also, said contacts, one or both of them, may be made relatively resilient and they are of course made of such light material and with such a light contact as not to interfere with the free vibration of the string.

In practice the extension 18 with its terminal 19 is usually fixed to the string at a point close to one of the supporting bridges and its lateral movement is therefore relatively slight and the impact of terminal 19 with the contact arm 16' is correspondingly slight.

These cooperating contacts are adjusted to energize the magnet at such times only as to produce propelling impulses which will be in time with the natural or free vibrations of the string, or in other words so that the magnet will attract the string only at such times as the string is moving toward the magnet in the course of its own natural vibrations.

There may be objections to making the contact member 16 or equivalent fixed or rigid and accordingly I have specified above that I may make it resilient. Therefore, because of the extremely minute movements of the string in its vibration and of the contact member as it is reacted upon by the string, it would be practically impossible to determine the initial relation of the contact arm 16' to the string otherwise than empirically. As is indicated in Figures 2 and 3, this initial position might be anywhere about the cross section of the string. By reason of the fact that the contact arm 16' makes contact with the string terminal 19 at a certain point in the swing of the string, such contact is tangential, as shown in both Figures 2 and 3,

and it is a very simple matter to adjust the contact arm 16' angularly about the cross section of the string or terminal until the proper position is found which, upon closing 5 of the circuit by the key 7, results in the production and sustaining of the characteristic tone of the string without any undesirable partials or overtones. When this position is found it is fixed, and it is obvious 10 that it will be different for different strings. The result of such adjustment is to bring about an operative accord between the electrical impulses of the magnet and the vibration phase of the particular string.

15 I claim:—

1. The method of electromagnetically vibrating a musical string which comprises controlling the circuit of the string-vibrating electromagnet through the medium of a 20 circuit contact carried by the string and a second contact engaged thereby and varying the point of engagement of said contacts angularly about said string until the impulses of the magnet are in synchronism with the 25 natural musical vibrations of the string.

2. The method of electromagnetically vibrating a musical string which comprises controlling the string-vibrating electromagnet through the medium of circuit contacts 30 controlled by the vibration of the string and adjusting the point of engagement of said contacts angularly in respect to the vibratory movement of the string to a point where the string-vibrating impulses of the electromagnet 35 will be in synchronism with the natural musical vibrations of the string.

3. The method of electromagnetically vibrating a musical string which comprises controlling the string-vibrating electromagnet through the medium of circuit contacts controlled by the vibration of the string and empirically fixing the point of engagement of said contacts at a point angularly related 40 to the vibratory movement of the string, 45 where the impulses of the magnet will be in synchronism with the natural musical vibrations of the string.

4. The method of electromagnetically vibrating a musical string which comprises controlling the energizing circuit of the string-vibrating electromagnet through the 50 medium of a contact outstanding from and carried by the string and a cooperating relatively stationary adjustable contact and adjusting said latter contact angularly about 55 the vibrating string-supported contact to bring the impulses of the magnet into synchronism with the natural musical vibrations of the string.

60 5. The method of electromagnetically vibrating a musical string which comprises controlling the energizing circuit of the string-vibrating electromagnet through the 65 medium of a contact carried by the string having an angularly extending terminal end

and a relatively stationary adjustable contact engaging said angular terminal and positioning said adjustable contact angularly about the terminal to bring the impulses of the magnet into synchronism with the 70 natural musical vibrations of the string.

6. The method of electromagnetically vibrating a musical string which consists in controlling an electromagnet for vibrating the string by means of a contact carried by 75 the string and a cooperating relative stationary contact and varying the position of said contacts angularly one about the other until the energization of said magnet is accomplished at such times as to produce propelling impulses by the magnet on the string in the direction in which the string is moving in the course of its natural musical vibrations.

7. In a device of the character described, 85 a vibratory string, an electromagnet for vibrating the same and a controlling circuit for said electromagnet comprising a contact carried by the vibratory string and a co-operating contact adjustable around said 90 first contact.

8. In a device of the character described, a vibratory string, an electromagnet for vibrating the same and a controlling circuit for said electromagnet comprising a contact 95 carried by the vibratory string and a co-operating relatively stationary contact, said contacts being relatively adjustable rotatably one about the other for varying the point of engagement therebetween.

9. In combination with a musical string and an electromagnet for vibrating the same, a controlling circuit for said magnet comprising a contact outstanding from the string, having an angularly extending terminal portion, and a cooperating contact engageable by said angular terminal and relatively adjustable thereabout to vary the point of engagement.

10. In combination with a musical string 110 and an electromagnet for vibrating the same, a controlling circuit for said magnet including a string-carried contact and a resilient contact angularly adjustable about said string-carried contact.

11. In combination with a musical string and an electromagnet for vibrating the same, a controlling circuit for said magnet including cooperating resilient contacts, one of said contacts being carried by the string 120 and said contacts being relatively adjustable angularly one about the other.

12. In combination with a musical string and an electromagnet for vibrating the same, a controlling circuit for said magnet 125 including cooperating resilient contacts, said contacts being relatively adjustable angularly one about the other.

13. In combination with a musical string and an electromagnet for vibrating the 130

same, a controlling circuit for said magnet including cooperative resilient contacts controlled by the vibratory movement of the string and said contacts being relatively adjustable angularly one about the other.

14. The method of electromagnetically vibrating a musical string which comprises controlling the string-vibrating electromagnet through the medium of circuit contacts controlled by the vibrations of the string and adjusting the point of engagement of said contacts angularly in respect of one to the other to a point where the string-vibrating impulses of the electromagnet will be in synchronism with the natural musical vibrations of the string.

15. The method of electromagnetically vibrating a musical string which consists in controlling an electromagnet for vibrating the string by means of a contact controlled by the string and a cooperating relatively stationary contact and varying the position of said contacts angularly one about the other until the energization of said magnet is accomplished at such times as to produce propelling impulses by the magnet on the string in the direction in which the string is moving in the course of its natural musical vibrations.

In testimony whereof I affix my signature.

SIMON COOPER.
